HORIZONTAL BROACH

William A. Hart, Detroit, Mich., assignor to
 Colonial Broach Company, a corporation of
 Michigan

Application February 15, 1936, Serial No. 64,062

5 Claims. (Cl. 90—33)

The present invention relates to machine tools, and in particular provides an improved fully automatic broaching machine.

Objects of the present invention are to provide an improved broaching machine of the fully automatic type, in the operation of which work may be positioned in broaching position, a broach then advanced through the work piece, the work piece then automatically moved away from broaching position, and the broach then returned to a starting position in readiness for a subsequent operation; to provide such a machine embodying, as independent but inter-controlled elements, a broach draw-head, a broach return head, a discharge mechanism, and means for operating such elements; to provide such a machine in which the broach draw-head advances the broach through the work and, subsequent to the action of the work discharge mechanism, returns the broach to a starting position in which the broach return head is effective to move the broach to a loading position, in which the broach is free of the work piece supporting mechanism and permits insertion of a new work piece; to provide such a machine embodying fluid pressure operated mechanism for operating the several broaching heads and the discharge mechanism; to provide such a machine in which the fluid pressure operated mechanism includes a cylinder and associated piston individual to each of the broaching heads, and a cylinder and associated piston individual to the discharge mechanism, which several fluid pressure mechanisms are inter-controlled to effect the above mentioned sequence of operation.

Further objects of the present invention are to provide an improved broaching machine as above generally stated, in which the discharge mechanism for the completed work pieces is rendered effective at the conclusion of a working stroke of the broach draw-head, to positively discharge a completed work piece from the machine prior to the return movement of the broach draw-head; and in which the return movement of the broach draw-head is dependent upon the prior discharge from the machine of the work piece by the discharge mechanism.

Further objects of the present invention are to provide an improved broaching machine as above generally stated, embodying means to accurately and readily position, and to positively lock, the work piece in broaching position; embodying means responsive to the completion of a broach working stroke for unlocking the locking mechanism; to provide such a machine em-

bodying locking mechanism for the work piece, jointly controlled by the starting means for the machine and by the broach working head; and to provide such an arrangement in which manual control means are provided to initiate a complete broaching cycle, which manual control means automatically renders the locking mechanism effective; and embodying means responsive to the completion of a broaching operation for unlocking the locking mechanism.

Further objects of the present invention are to provide an improved automatic broaching machine of the above generally stated character, embodying a novel disposition of the several operating and control parts, resulting in a more compact and generally more efficient machine; and to provide an automatic broaching machine embodying generally improved details of construction.

With the above and other objects in view which appear in the following description and in the appended claims, a preferred but illustrative embodiment of the present invention is shown in the accompanying drawings, throughout the several views of which corresponding reference characters are used to designate corresponding parts, and in which:

Figure 1 is a perspective view, in side elevation, of the improved machine;

Fig. 2 is a view, in vertical section, taken along the line 2—2 of Fig. 1;

Figs. 3 and 3A, collectively, are a view in vertical section, taken along the line 3, 3A—3, 3A of Fig. 2, these figures being conveniently considered together by placing Fig. 3A immediately to the right of Fig. 3;

Fig. 4 is a sectional view in top plan, taken along the line 4—4 of Fig. 1;

Fig. 5 is a fragmentary sectional view, taken along the line 5—5 of Fig. 4;

Fig. 6 is a fragmentary view in vertical section, taken along the line 6—6 of Fig. 5;

Fig. 7 is a fragmentary view in vertical section, taken along the line 7—7 of Fig. 5;

Fig. 8 is a diagrammatic view of suitable control mechanism for effecting the preferred operating sequence of the machine; and

Fig. 9 is a view of an alternative broach head construction which may be used in the practice of the invention.

Referring first to the general view, Fig. 1, the preferred construction is of the horizontally disposed type, and comprises generally a supporting frame structure 10 provided with upstanding centrally disposed but spaced abutments 12 and 55

14 between which the work piece 16, illustrated as a conventional cylinder block for an internal combustion engine, is received and is slidable inwardly and outwardly upon a work supporting table 18. The shank 20 of the draw-head, hereinafter described in more detail, is rigidly but removably secured by nuts 22 to a boss 24 positioned above but axially parallel to a working cylinder 26 and connected thereto by ribs 28. 5 Cylinder 26 is slidable within ways 30 formed within the machine frame. The broach return head, not shown in Fig. 1, described in more detail hereinafter, is also rigidly but removably connected to a crosshead 32, slidable on longitudinally extending guide rods 34 and 36 which extend between the abutment 14 and a similar abutment 38 positioned at the left-hand end of the machine as viewed in Fig. 1. Crosshead 32 is operated by a piston in a cylinder 40 suitably housed within a frame portion 42 which is positioned above and extends between the previously mentioned abutments 12 and 14. 10

It will be noted that the operating mechanism for the broach heads is thus disposed in axially displaced but longitudinally overlapped relation, the cylinder for the broach return head being disposed substantially directly above the working position of the machine and the cylinder for the broach draw-head being disposed substantially 15 directly beneath the working position. With this arrangement, the overall length of the machine is required to exceed the overall spacing between the abutments 12 and 14 which define the working position only sufficiently to accommodate the desired length of stroke of the broach heads. 20

The discharge mechanism hereinafter described in more detail, does not appear in Fig. 1, but as shown clearly in Fig. 2, comprises generally a cylinder housing 44 positioned at the rear of the machine substantially centrally thereof in position so that the plunger 214 thereof may force the work piece 16 forwardly of the machine to a position in which it is free of the path of travel of the broach. 25

The necessary control mechanism for operating the broach is conveniently disposed upon the front of the machine for ready operation by the operator thereof and, as illustrated, causes the manual starting handle 48, which, as hereinafter described, serves to initiate a complete broaching cycle and also serves to actuate mechanism to positively lock the work piece 16 in the broaching position shown in Fig. 1; an emergency stop handle 50; and suitable indicating mechanism illustrated as a meter 52, which may serve to indicate the load upon the broach working head. 30

Considering the above mentioned elements in more detail and referring particularly to Figs. 3, 60 3A and 4, the broach draw-head, designated as a whole as 60, is of the automatic locking and unlocking type, embodying the previously mentioned tubular shank 20, the bore of which freely slidably receives the end of broach 62, an outer sleeve 64, and a plurality of radially disposed locking pins 66, which are received in radially extending passages formed in shank 20 and in corresponding angularly spaced recesses 68 formed in sleeve 64. 65

Sleeve 64 is slidable axially of shank 20 and is continuously urged to the left, as viewed in Fig. 70 3A, by a compression spring 74 seated between an inwardly extending lug 75 formed on sleeve 64 and an axially aligned shoulder formed in shank 20. The spring 74 thus limits rightward move- 75

ment of sleeve 64 (as viewed in Fig. 3A) and opposite movement thereof is limited by a removable stop pin 70 secured in sleeve 64, the end of which is received in a slot 72 formed in shank 20. 5

The locking pins 66 are freely movable within the associated radial slots formed in shank 20, the inward movement thereof being limited either by engagement of the chamfered inner ends thereof with broach 62 or by engagement between stop pins 76 secured thereto which ride in slots formed in shank 20. The outward movement of locking pins 66 is limited by engagement of the outer ends thereof with the surface of sleeve 64. 10

The parts of broach head 60 are shown in the 15 broach released position, in which sleeve 64 is forced to the right relative to shank 20, as viewed in Fig. 3A, against the force of compression spring 74, having been moved to this position at the conclusion of a return movement of cylinder 26 by 20 the engagement of sleeve 64 with one or more adjustable stops 80 which comprise studs threaded into the wall of the previously mentioned centrally positioned abutment 12. With the parts in this position broach 62 may be freely removed 25 from broach head 60, the removal thereof camming the upper locking pin 66 upwardly out of the locking notch 82 formed in the shank on broach 62 into the associated recess 68, and the lower locking pin having fallen by gravity to a 30 corresponding retracted position. Upon removal of broach 62, the upper locking pin 66 may be expected to fall inwardly of the locking head 60, under the influence of gravity, the inward movement thereof being limited as previously described 35 by the stop pin 76 associated therewith. The lower pin 66 remains supported by the recess 68 associated therewith formed in the sleeve 64. With the parts in the illustrated positions, broach 62 may also be freely inserted into head 60, the 40 inserting movement having no effect upon the lower locking pin 66, but camming the upper locking pin 66 upwardly sufficiently to permit the broach to enter and finally permitting locking pin 66 to again fall into the locking notch 82 of the 45 broach. If locking head 60 is now released from the stop 80, as by movement to the right, as viewed in Fig. 3A, of boss 24, sleeve 64 moves to the left relative to shank 20 under the influence of compression spring 74, moving the recesses 50 68 out of registry with the locking pin 66 and moving the sleeve portion 84 into registry with the end of the locking pin, sleeve 64 being provided with the angled cam shoulders 86 between the recesses 68 and the sleeve portion 84, which cam the locking pins 66 inwardly of the head and positively retain them in locking position. 55

The cylinder 26, which actuates the broach draw-head 60, is slidably supported upon ways 30 formed in the machine frame, as previously 60 stated, and reciprocates along said ways from the starting position thereof shown in the various figures to a limit position to the right of the position shown. Cylinder 26 and its cooperating piston 90 are preferably constructed in accordance 65 with the disclosures of the co-pending application of the present applicant, Serial No. 42,619, filed September 28, 1935, and assigned to the same assignee as the present application. As there described in more detail, cylinder 26 comprises an outer casing and an inner cylinder 92 within which the piston 90 is positioned. Piston 90 is secured at the end of a piston rod formed of two telescoped tubes 94 and 96, which extend through an opening formed in a closure plate 98 70 75 75

secured at the left-hand end of cylinder 26, as viewed in Fig. 3, and are secured in a head 100 which in turn is suitably secured to and supported by the machine frame 10. A suitable packing gland 102 is interposed between the closure plate 98 and the outer tube 96.

The inner tube 94 is threaded into an axial bore 104 formed in piston 90 and thus communicates with the interior of casing 92 on the right-hand side of piston 90. The outer tube 96 is provided with one or more radial ports 106 through which communication is had between the interior of tube 96 and the interior of casing 92 on the left-hand side of piston 90. The head 100 is provided with ports 108 and 110 which communicate respectively with tubes 94 and 96 and which are selectively connected through suitable lines 112 and 114 to a suitable source of fluid pressure, through the hereinafter described control system.

It will be evident by connecting line 112 to the source of pressure and line 114 to exhaust, fluid under pressure is admitted to casing 92 on the right-hand side of piston 90 and is exhausted through tube 96 from the casing portion on the left-hand side of piston 90, thus causing cylinder 26 to move bodily to the right, as viewed in the several figures. By reversing the connections, fluid is exhausted from the chamber space to the right of piston 90 and is admitted to the chamber space to the left of piston 90, thus causing cylinder 26 to move bodily to the left, as viewed in the several figures.

In the construction shown in detail in Figs. 3 and 3A a locking head 120 corresponding in all respects to the locking head 60 described above, is provided in connection with the return broaching head 122, which is disposed for actuation by the previously identified cylinder 40 and associated elements. It is considered unnecessary therefore to further describe the locking head 120 except to note that in the drawings, stop pins 125 are disposed in the path of the head to effect the releasing movement thereof, which correspond to the releasing studs 80. It will be understood that head 120 is shown in the broach releasing position, in which broach 62 may freely be removed therefrom or inserted therein and that head 120 assumes a locking position upon retraction thereof out of range of the stop pins 125, in the manner described with reference to head 60.

As an alternative to the locking head 120, a releasable head of the type shown in Fig. 9 may be used, in which figure the head comprises a sleevelike member 150 provided with a plurality of radially extending passages 152, each of which accommodates a spring pressed detent 154 which may be retracted by applying a predetermined separating force between the broach 62 and the head, and which are resiliently urged to locking position by the associated compression springs 158. In certain instances, a broach head of this character is satisfactory for use in connection with the return mechanism, since the principal purpose thereof is to move the broach between starting and loading positions, during which time no broaching action is effected by the broach.

The shank 122 of return broach head 120 is slidably received in a boss 124 which forms part of the cross head 32 and is secured in place axially thereof by a nut 128, which may be turned down to force the end of boss 124 against a shoulder 130 formed in shank 122. Crosshead 32, as best shown in Fig. 4, comprises the two bosses 132 and 134, which are supported by and disposed to slide along the previously mentioned guide rods 34 and

36 respectively, the opposite ends of which are supported in openings 140 and 142 formed in the abutment 14 respectively and in corresponding openings formed in the end abutment 38. The crosshead 32 is connected by ribs 160 to a boss 162 which is positioned above and intermediate the two bosses 132 and 134, and consequently as best shown in Fig. 4, is substantially directly over the boss 124 which carries the broach return head 120.

The piston rod 164 associated with the broach return cylinder 40, is axially fixed in boss 162, between the lock nuts 166 and 168, and extends through a suitable packing gland 170 associated with the closure plate 172 of cylinder 40, terminating in a conventional piston 174 which is slidable within the casing 176 of cylinder 40. Cylinder 40 as a whole, as previously described, is supported above the level of the loading position of the machine within the frame portion 42. The closure plate 172 associated with cylinder 40 is provided with a pocket 178 which communicates with a port 180 to which a suitable fluid supply line may be connected, to admit and exhaust fluid from the chamber space on the left-hand side of piston 174. The corresponding closure plate 182 for the right-hand end of cylinder 40 is provided with a corresponding pocket 184 which communicates through a port 186 with a similar supply line 188 through which fluid may be admitted and exhausted from the chamber space on the right-hand side of piston 174. The control mechanism for selectively connecting the ports 180 and 186 to a source of fluid pressure and to an exhaust line is described hereinafter.

Considering the work supporting and discharging mechanism in more detail, the previously described table 18 includes a bracket 190 which extends outwardly from the machine at the front thereof and forms a support upon which the work piece 16 may be rested prior to being moved to the working position, and upon which the work is discharged by the discharge mechanism at the conclusion of a broaching operation. Immediately to the left of the bracket portion 190, as viewed in Fig. 2, the work table 18 includes a supporting table structure, the particular formation of which, it will be understood, depends upon the form of the work piece to be broached, and, in the illustrated embodiment, comprises the two spaced table sections 192 and 194. Guide strips 196 and 198 are associated with the table portions 192 and 194 respectively and constitute the direct supports upon which the work piece 16 rests. Corresponding guides 200 and 202 are supported within the machine frame and are positioned directly above the guides 196 and 198, respectively, the vertical spacing between the related pairs of guides being substantially equal to the vertical dimension of the work piece 16, which is accordingly rather snugly received between the four guides. During a broaching operation, the right-hand end 16a of the work piece 16 bears against a plate 204, positioned in bearing relation to the previously mentioned abutment 12. Removable spacing blocks, such as 206, are preferably interposed between the left-hand end 16b of the work piece and the abutment 14.

The discharge mechanism 44 comprises generally, as best seen in Fig. 4, a cylinder 216 secured within a bracket 212 mounted upon the machine frame at the rear side thereof and provided with a piston rod 214 with which a suitable piston (not shown) is associated, effective to move piston rod 214 from the illustrated retracted position through

5

55

60

65

70

75

a forward or working stroke to the right, as viewed in Fig. 2, and also to move it through a return stroke to the left, as viewed in Fig. 2.

The end of piston rod 214 bears against a head 5 or bar 216 guided within a track or way 218 which is supported by the machine frame and which, as best seen in Figs. 3 and 3A, is positioned intermediate and somewhat below the work table portions 192 and 194. The block 216 bears directly 10 against the rear side of work piece 16 and when in its retracted position, permits insertion of work piece 16 to the working position with reference to the broach 162 but forms a positive limit to such movement, being adjusted to block movement 15 of work piece 16 when the latter reaches a position of substantial alignment with broach 162. As will be evident, however, an outward movement of block 216, as effected by the discharge mechanism 44, positively moves the work piece 20 away from the working position cut upon the external supporting bracket 193. Any desired mechanism may be utilized to convey the completed work piece away from bracket 193 and to convey new work pieces thereto, as well as to feed the 25 new work pieces from the loading position to the working position, this operation being effected manually in accordance with the illustrated construction.

In further accordance with the preferred embodiment of the present invention, means are 30 provided to positively lock the work piece 16 in the working position during the broaching action and, as hereinafter described in more detail, this mechanism is arranged for control by and in 35 accordance with the operation of the machine starting handle and of broach head 60. Referring particularly to Figs. 4, 5, 6 and 7, locking pins 220 and 222 are slidably supported within sleeves 224 and 226, respectively, which are fitted into 40 passages formed in the machine frame 10 and, as shown in Fig. 4, are positioned to engage the base of work piece 16 at points adjacent the respective ends thereof and at or near the transverse center thereof. It will be understood that 45 the work piece 16 is provided with recesses into which the tapered ends 228 and 230 of the pins are received, which recesses are accurately located relative to the work piece so that when the pins are engaged therein the work piece 16 is positively maintained in accurate alignment with the 50 path of travel of the broach.

The raising and lowering of locking pins 220 and 222 between a lowered retracted position, and the raised locking position illustrated in Figs. 5 and 7, is effected by a cam bar 232 which is 55 slideable within a passage 234 formed in the machine frame and is provided with two pairs of cam shoulders 236, 238, 240 and 242, respectively. Bar 232 passes through transverse openings formed 60 in the pins 220 and 222, respectively, and in the associated supporting sleeves, the openings in the pins being provided with angled faces 244 and 246 and 248 and 250, respectively, to cooperate 65 with the corresponding cam surfaces of the bar. 70 It will be understood that with the parts in the positions illustrated in Fig. 5, pins 220 and 222 are positively projected to the upper or locking position and are supported therein by the bar 232, the straight upper portions of which are in 75 supporting relation to corresponding portions of the passages through the pins. Movement of bar 232 to the right, as viewed in Fig. 5, however, brings the relieved portions 252 and 254 thereof into registry with pins 220 and 222, respectively. 75 The bar movement positively retracts the pins,

because of the camming relationship between the angled surfaces 238 and 246 and the corresponding surfaces 242 and 250. Similarly, movement of bar 232 from a position to the right of the illustrated position to the illustrated position results in positively projecting pins 220 and 222 to the illustrated position, the projecting movement being effected by the camming relationship between the angled surfaces 244 and 236 and the correspondingly angled surfaces 248 and 240. 10

Referring particularly to Figs. 5 and 6, the left-hand end of bar 232, as viewed in Fig. 5, is provided with rack teeth 260 with which a pinion 262 meshes. Pinion 262 is carried by a trunnion 264 journaled in bosses 266 and 268 either forming 15 part of or suitably secured to the main machine frame 10.

The operating handle 48 (Figs. 1 and 6) which, as hereinafter described, preferably also controls the fluid pressure control connections to initiate 20 the starting of a complete broaching cycle, is suitably secured upon a shaft 270, journaled within the machine frame, and provided with a pinion 272. A rack bar 274, provided with rack sections 276 and 278, extends between the pinions 272 and 25 262. As appears clearly evident in Figs. 1, 5, 6 and 8, rotation of handle 48 in a clockwise direction correspondingly rotates pinion 272 and, through rack bar 274, also correspondingly rotates pinion 262 to actuate locking bar 232 to the left 30 from the unlocked to the locked position described above. A link 280 is connected to bar 232 and, as shown in Fig. 1, extends to a suitable control head 282 adjacent the limit position of cylinder 26. As shown in Fig. 8, the approach of cylinder 26 35 to its right-hand limit position brings a cam 329 into engagement with and rotates a bell crank 322. Bell crank 322 is connected to link 289 through push rods 323 and 324 and bell cranks 326 and 328. Push rod 324 has a lost motion connection with bell crank 328 and the above leftward movement of link 280 lifts a collar 330 on push rod 324 into engagement with bell crank 328. Thus, when bell crank 328 is rotated in response to the arrival of mechanism 26 at the 40 end of its stroke, bar 280 and handle 48 are restored to their original positions.

The present invention embraces within its scope the provision of automatic control mechanism responsive to operation of the previously mentioned 50 control handle 48 for controlling the locking and unlocking mechanism associated with the work piece 16 and described with reference to Figs. 5 and 6, and for initiating the sequential and interlocked operation of the various actuating mechanisms 26, 40 and 44, for the broach draw-head 60, the broach return head 120, and the discharge mechanism 44. The mechanical elements involved in the automatic control of the sequential movements of the latter elements are housed 55 within the lower part of the enclosing machine frame, and thus do not appear in the figures thus far described. These elements are shown in the remaining Figure No. 8. Referring to Fig. 8, the working, return, and discharge mechanisms 26, 40, and 44, may be provided with valves 300, 302 and 304, respectively, which are individual thereto and each of which is preferably of the type which may be successively actuated from one operating position to another by unidirectional movement of an operating shaft associated therewith. The valve 300 associated with the cylinder 26 is adapted to provide an off position in which flow through the valve is prevented, and consequently cylinder 26 is maintained at rest; an on 70 75 valve 302 associated with the cylinder 40 is adapted to provide an off position in which flow through the valve is prevented, and consequently cylinder 40 is maintained at rest; an on valve 304 associated with the cylinder 44 is adapted to provide an off position in which flow through the valve is prevented, and consequently cylinder 44 is maintained at rest; an on 75

forward position, in which connections are completed to effect movement of cylinder 26 to the right, as viewed in the figures; a second off position in which cylinder 26 is maintained at rest; 5 and an on return position in which connections are completed through the valve to cause cylinder 26 to move to the left through a return stroke, as viewed in the figures. The valve 302, associated with the return cylinder 40, is similarly arranged.

The valve 304 associated with the discharge cylinder 44 is provided with only three individual operating positions including an on forward position in which the valve completes suitable connections to effect a discharge or forward movement of the discharge mechanism; a reverse position in which the valve completes connections to effect a return movement of the discharge mechanism; and an off position in which flow through 15 the valve is prevented and the discharge mechanism is maintained in its withdrawn or retracted 20 normal position.

Valve 300 is illustrated as provided with an operating shaft 306, which is disposed for notch- 25 ing rotation in a clockwise direction by the cranks 306a, 306b, 306c, and 306d, each of which is connected thereto by a lost motion or ratchet connection, so that rotation of an individual crank in a clockwise direction is effective to correspondingly rotate arm 306 one notch or the distance 30 between successive operating positions in the same direction, but so that arm 306 may be rotated independently of such particular crank. Valve 302 is provided with a similarly arranged 35 operating shaft 308 having associated therewith in the manner just described four operating cranks 308a, 308b, 308c and 308d. Valve 304 is provided with a corresponding operating arm 310, provided with similarly associated cranks 310a, 40 310b and 310c. As clearly appears in Fig. 8, crank 308a is disposed for manual movement by the previously identified handle 48 to thereby initiate the operating cycle. For this purpose the shaft 270 associated with crank 48 is connected 45 to the crank 308a through a push rod 332. Similarly, cranks 306a and 308b are disposed for actuation by the return mechanism 40 at the conclusion of a forward stroke thereof, substantially 50 at the same time that piston 174 associated therewith reaches the starting position illustrated in the previously described figures. For this purpose the cross-head 32 associated with cylinder 40 carries a cam 334 which engages and rocks a bell crank 336 at the conclusion of the just mentioned forward stroke. Bell crank 336 is connected to crank 308b through push rod 338 and is also connected to crank 306a through the additional push rod 340. Cranks 306b and 310a are disposed for actuation by the working mechanism 26 when said mechanism reaches the end 55 of its working stroke, that is, the extreme right-hand position thereof as viewed in the several figures. This action is effected through the operation of the previously described bell crank 322, which operates a push rod 342 through the push rod 323. Push rod 342 in turn is connected to the cranks 310a and 306b. Crank 310b is disposed for actuation by the discharge mechanism 44 when said mechanism reaches its forward or extended position after having moved a completed 60 workpiece out of the machine. For this purpose the head 216 associated with cylinder 44 is provided with a cam 343 which engages and locks a control lever 346. Lever 346 is connected to crank 310b through a push rod 344. Cranks 310c and

306c are disposed for actuation by the discharge mechanism 44 upon the arrival thereof at its normal or retracted position. This action is effected through the engagement of cam 343 with a lever 348. The lever 348 operates cranks 310c 5 and 306c through push rods 350 and 352. Cranks 306d and 308c are disposed for actuation by the working mechanism 26 upon the arrival thereof at substantially the position shown in the previously described figures, that is, at the starting 10 position. This action is effected through push rods 354 and 356, which are actuated by a bell crank 358. Bell crank 358 is engaged by the cam 320 when cylinder 26 reaches its starting position. The remaining crank 308d is disposed for 15 actuation by the return mechanism 40 upon the return thereof to its extreme left-hand position, that is, the loading position of the machine. This action is accomplished through a push rod 360 which is operated by the cam 334 through a bell 20 crank 361. It will be noted that each of the cam operated bell cranks is provided with a return spring such as 362 (bell crank 358) to restore the respective bell cranks and push rods to the original positions thereof as soon as the cams 25 pass out of operating engagement therewith.

Valves 300, 302 and 304 each communicate through lines 312, 314 and 316, respectively, with a suitable manifold 318 which may lead to a suitable sump. The valves also are connected, 30 through suitable lines 320, 322 and 324, with a suitable distributing manifold 326 which leads to a suitable source of fluid pressure which may comprise the motor driven pump 328, shown in Fig. 1, and positioned within the machine frame. 35 Preferably, and as illustrated, a suitable emergency stop valve 330 is positioned in the manifold 326 and through suitable connections (not shown) is arranged for control by the previously mentioned emergency stop lever 50 positioned 40 upon the front of the machine, as shown in Fig. 1.

Operation as a whole

Considering now the operation of the machine 45 as a whole, the parts of the machine are, for convenience, shown in Figs. 1 through 8 in the starting positions thereof. In practice, with the illustrated control arrangement (Fig. 8), the parts normally occupy positions of rest corresponding 50 to a loading position in which the discharge and working mechanisms 44 and 26 occupy the positions shown and the return mechanism 40 occupies an extreme left-hand position in which head 120 supports broach 62 in a retracted or 55 loading position. In the loading position broach 62 does not interfere with the removal and insertion of work piece 16.

Assuming a work piece 16 has been moved into the position shown therefor in dotted lines in the respective figures, in which position, as previously described, it is rather accurately fitted between the upper guides 200 and 202, lower guides 196 and 198, face plate 204, spacing bar 206 and head 216, the manual starting handle 48 may be 60 actuated to initiate an automatic operating sequence, and to project the locking pins 220 and 222 into the recesses provided therefor in the work piece 16. The locking action is effected, as previously described with reference to Figs. 5 65 and 6, through bar 232 which responds to rotation of handle 48 and project pins 220 and 222 upwardly. This projecting action corrects any misalignment of the work piece which may exist, due to the manual insertion of the work piece, 70 75

and brings the work piece into accurate axial alignment with broach 62. This locking movement also pulls link 280 (Figs. 1, 6 and 8) to the left, presetting it for actuation by cylinder 26 5 through push rod 324. Handle 48 remains in the operated position for the time being.

Rotation of handle 48 also rotates crank 308a associated with valve 302 through one step in a clockwise direction, moving valve 302 to the on 10 forward position in which it is effective to complete connections to return mechanism 40 to cause it to move to the right carrying broach 62 therewith. This movement advances the forward end of broach 62 through work piece 16 and ultimately 15 moves the leading end of broach 62 into the broach draw-head 60 which, in the starting and loading positions of the machine, is in a position to freely receive broach 62, as previously described.

20 As the return mechanism 40, carrying broach 62 with it, approaches the right hand end of its stroke, the return broach head 120 engages the stop pins 125 (Fig. 3), resulting in the release therefrom of broach 62. At or about the same 25 time, through push rod 338, the movement of return mechanism 40 actuates crank 308b, associated with valve 302, moving valve 302 to an off position, and thus interrupting the flow of fluid therethrough and bringing return mechanism 40 30 to rest at the starting position.

Through push rods 338 and 340, the arrival of return mechanism 40 at the right hand end of its stroke also actuates crank 306a, associated with valve 309, and throws this valve to an on 35 forward position, completing fluid connections to cause a forward or working movement of the broaching cylinder 26. At the beginning of this working movement, and as the head 60 thereof moves away from the stop pins 80, the locking 40 pins 66 are cammed into positive locking relation to broach 62, and firmly secure it within head 60. Accordingly, the working movement of cylinder 26 positively draws broach 62 through the work piece 16.

45 As cylinder 26 approaches its right-hand limit of travel, it actuates link 280 (Figs. 1 and 6), through push rod 324 and bell crank 328, and also operates cranks 306b and 310a. Actuation of link 280 correspondingly moves lock bar 232 50 and pins 220 and 222 to retracted positions, in which the latter do not interfere with the discharge of work piece 16 from the machine. This movement also returns handle 48 and crank 308a to their initial positions. Crank 306b throws 55 valve 300 to the off position, bringing working mechanism 26 to rest. Crank 310a throws valve 304 to the on forward position, resulting in actuating the discharge mechanism 44 to positively move the work piece 16 out of the machine upon 60 the platform 190. It will be understood that at the time cylinder 26 is brought to rest, the trailing end of broach 62 is beyond and free of the work piece 16 and thus does not interfere with the discharge movement thereof.

65 When discharge mechanism 44 approaches the limit of its stroke, by which time the work piece 16 is entirely discharged from the machine, the movement thereof actuates crank 310b, through push rod 344, throwing valve 304 to a reverse 70 position and resulting in a return movement thereof. Upon completing the return movement, discharge mechanism 44 actuates crank 310c (through push rod 350) to throw valve 304 to the off position, thereby bringing the discharge mechanism to rest; and also actuates crank 306c to

throw valve 309 to its on return position, in which it is effective to complete connections to cause a return movement of the working mechanism 26.

As return mechanism 26 approaches the starting position, the sleeve 64 forming part of the 5 broach head 60 associated therewith engages the stop pins 80 and is thereby moved relatively to the shank 20, permitting the locking pins 66 to be moved radially outwardly, to thereby permit removal from broach head 60 of broach 62. At 10 or about the same time, through push rods 354 and 356, return mechanism 26 actuates crank 306d to bring valve 300 to the initial off position, bringing return mechanism 26 to rest at the starting position. Return mechanism 26 also actuates crank 308c, to throw valve 302 to the on 15 return position, resulting in a movement to the left of return mechanism 40. The approach of broaching cylinder 26 to the starting position moves the left-hand end of broach 62 into the 20 return locking head 120, so that as locking head 120 recedes from the stop pins 124, the locking pins associated therewith are positively cammed into locking relation to broach 62, resulting in broach 62 being carried along with return mech- 25 anism 40.

As return mechanism 40 approaches its initial left-hand limit or loading position, it actuates crank 306d, through push rod 360, throwing valve 302 to its initial or off position, bringing the re- 30 turn mechanism to rest at the loading position. At the conclusion of the above described cycle, accordingly, the control mechanism is in its initial condition, all of the valve mechanisms 35 being in their initial off position and the various operating parts being at rest. The machine is thus in readiness for another and duplicate cycle.

Although specific embodiments of the present invention have been described, it will be evident 40 that various modifications in the form, number and arrangement of parts may be made within the spirit and scope thereof. It will also be evident that various elements of the present invention may be utilized independently of other elements thereof and may be used for purposes other 45 than the specific purposes described. The described embodiments, accordingly, are to be regarded in an illustrative, and not in a limiting, sense. 50

What I claim is:

1. A broaching machine comprising, in combination, a work table for supporting work in broaching position relative to a broach; discharge mechanism movable between retracted and projected positions and effective upon being projected to move said work along said table out of the path of said broach and effective when in said retracted position to form a stop to preliminarily position said work relative to said broach; and locking means for accurately positioning and locking said work in said broaching position. 55

2. A broaching machine comprising, in combination, a work table for supporting work in broaching position relative to a broach; starting means for said machine; a draw head for drawing a broach through said work from a starting position to a limit position and for returning said broach to said starting position; discharge mechanism for moving said work along said table 60 out of said broaching position; means for locking said work in broaching position; means actuated by said starting means for actuating said locking means to lock said work; means actuated by said broach head as it approaches said limit 65 70 75 80 85 90 95 98

position for actuating said locking means to unlock said work and for actuating said discharge mechanism to discharge said work; and means actuated by movement of said discharge mechanism for causing said broach head to return to said starting position.

3. A broaching machine comprising, in combination, a work supporting table, a broach draw-head operable to draw a broach through a working and a return stroke, said head being effective during said working stroke to draw said broach from a starting position through said work and effective during said return stroke to return said broach to said starting position, discharge mechanism effective to move said work out of the path of travel of said broach, means actuated by said draw-head upon completion of the working stroke thereof for causing said discharge mechanism to move said work out of the path of travel of said broach, and means actuated by said discharge mechanism after it has completed said movement of said work for causing said draw-head to move through said return stroke.

4. In a broaching machine, the combination of a work table for supporting work in broaching position relative to a broach; means for moving said broach through an operating stroke relative to said work; a pair of projectable and retractable locking pins adapted upon being projected to enter cooperating recesses formed in said work to lock the same in said broaching position; means including a link extending between said pins and having cam shoulders formed thereon for positively moving said pins in retracting and projecting directions; a start control for said broach moving means operable to move said link in a pin projecting direction; and means actu-

ated by said broach moving means for moving said link in a pin retracting direction.

5. A broaching machine comprising, in combination, a work supporting table, a broach draw-head operable to draw a broach through a working and a return stroke, said head being effective during said working stroke to draw said broach from a starting position through said work and effective during said return stroke to return said broach to said starting position, discharge mechanism effective to move said work out of the path of travel of said broach, a broach return head operable to deliver said broach to said broach draw-head at the beginning of a said working stroke and to receive said broach from said broach draw-head at the conclusion of said return stroke, said broach return head being arranged to withdraw said broach to a retractable position so as to permit said work to be delivered to and discharged from said work supporting table, means actuated by said broach return head when it delivers said broach to said broach draw-head for causing said broach draw-head to move through said working stroke, means actuated by said broach draw-head upon completion of said working stroke for causing said discharge mechanism to move said work out of the path of travel of said broach, means actuated by said discharge mechanism after it has completed said movement of said work for causing said broach draw-head to move through said return stroke, and means actuated by said broach draw-head at the conclusion of said return stroke for causing said broach return head to move said broach to said retracted position.

WILLIAM A. HART.
